UNITED STATES PATENT OFFICE.

DAVID E. BLAIR, OF MONTREAL, QUEBEC, CANADA.

DUMP-CAR.

1,007,324.

Specification of Letters Patent. Patented Oct. 31, 1911.

Application filed September 8, 1909. Serial No. 516,874.

To all whom it may concern:

Be it known that I, DAVID E. BLAIR, of the city of Montreal, in the Province of Quebec and Dominion of Canada, have invented certain new and useful Improvements in Dump-Cars, of which the following is a full, clear, and exact description.

This invention relates to dump cars of the type having side doors, which are automatically released and opened when the car is tilted to one side so as to open up the whole side of the car for the discharge of the load. The car body is mounted upon the center sills of the under frame and is supported centrally thereof upon rolling hinges so constructed that when the loaded car is released from its normal horizontal position, it will tilt to one side automatically to discharge its load.

20 The main object of the invention is to provide a simple, durable, efficient and comparatively inexpensive construction, that will be sufficiently strong to carry the load and resist the various strains to which it is subjected; that can be quickly and easily tilted to one side to discharge its load, and that can be returned to its normal position with great facility.

A further object is to provide a car which 30 will be particularly adapted to carry loads such as ballast and the like; that can be discharged lengthwise along one side of the car, said car being provided with means to prevent the ballast from spreading between 35 the car trucks, thus detaining the car unnecessarily on lines where the passenger traffic is heavy.

For particulars of body construction, reference may be had to my complementary 40 specification, Ser. No. 516,875.

In the drawings which illustrate my invention:—Figure 1 is a plan view of a car, the right half showing the body of the car, and the left showing the under frame. Fig. 45 2 is a side elevation of the dumping car, the left half being shown in central longitudinal section. Fig. 3 is an elevation of the rear end of the car. Fig. 4 is a vertical transverse section on the line 7—8 of Fig. 1. Fig. 5 is 50 an enlarged vertical transverse section on the line 9—10 of Fig. 1. Fig. 6 is an enlarged, vertical, longitudinal section on the line 11—12 of Fig. 5.

Referring to the drawings, 13 designates 55 a car body comprising floor plates 14, end walls 15, and transverse diaphragms or

partitions 16. One side wall of the car is fixed, but the opposite side wall consists of a series of doors 17 extending from end to end of the car, said doors being hinged at 60 the bottom to swing outwardly and downwardly. The car body is stiffened by a series of longitudinal angle bars, the center angle upon which the body is supported being designated by the numeral 18 and the 65 angles on each side of the center, by the numeral 19. The doors 17 are operated by means of a lock shaft 20, carrying door latches 21, said shaft 20 being actuated by means of a lever 22, pivotally connected to 70 a link 23 secured to the under frame of the car. When the doors drop, they are supported at a suitable angle to prevent the load from spreading underneath the car by means of buffers 24 carried upon hangers 25, said 75 hangers being held in position by means of the pivoted links 26, which are also secured to the under frame of the car.

The under frame comprises a center sill 80 consisting of the channel beams 27 which are connected and supported by means of suitable plates riveted thereto in the usual manner. At one side of the underframe, a side sill 28 extends from end to end of the car, while at the opposite side, the side sills 85 29 are provided adjacent the car trucks. The car is carried upon bolster frames 30 under which the trucks are located.

31 designates the end sills of the underframe, and 32 the tie plates connecting the 90 channel beams of the center sill. The bolster frame is strengthened and supported by means of the gusset plates 33.

34 designates the transverse beams extending from the center sill 27 to the side sill 28, 95 said beams carrying the shaft which operates the tilting mechanism. The channel beams of the center sill 27 are connected at intervals by means of cover plates 36 which are provided with apertures 37, the purpose of 100 which will be hereinafter explained.

The car body is supported upon a series of castings 39, the outer edge of which is in the form of a segment, and these castings form rolling hinges upon which the car is 105 pivoted and tilted to one side to discharge its load. These curved hinge members are secured to the center longitudinal angle beam 18 at one side and to the next adjacent angle beam 19 which supports the car floor, 110 as clearly shown in Fig. 5. The hinge members are further riveted or bolted to the

floor plates adjacent the transverse dia-
phragms. It will be seen that the curved
edge of the hinge member is toward the
side to which the car is tilted, said hinge
member being provided with a toe-piece 40
which carries the load and prevents the car
from tilting back too far when being re-
turned to its normal position. The end
motion of the car is prevented by means of
bearing plates 38 adjacent the hinges. The
curved edge of the hinge member 39 is pro-
vided with a series of teeth 42 which op-
erate in the apertures or slots 37 in the
plates 36. The car being mounted upon the
rolling hinges 39 may thus be tilted to one
side, as shown in dotted lines in Fig. 4, and
the center of support of the car body is
preferably out of line with the central axis
of the car in order that it may dump itself
automatically when released.

The operation of tilting the car is accom-
plished by means of a shaft 43 which is
preferably squared, being provided at in-
tervals with bearings 44, which operate in
bearing plates 45. Pinions 46 are mounted
on the shaft 43 and engage or mesh with
the teeth of the racks 47, which are secured
to the angle bars 48, located between the
floor bars 19 on the opposite side of the car
from the doors. The racks 47 are provided
with projecting toe-pieces 49 at their lower
ends which engage the guide rolls 50 mount-
ed on the plates 51 and prevent the car
from tilting too far downwardly. Gusset
plates 52 are provided to brace the end sills
31, and diagonal braces 53 connect said gus-
set plates with the center sill. The front
end of the car may be provided with an
operating platform 54 and the rear end with
a platform 55.

The operation of the tilting and dumping
mechanism will be readily understood
from the foregoing description. The car
is loaded in its normal level position and is
held in place by the engagement of the pinion
46 with the rack 44, the shaft 43 being
locked and released by any well known
mechanism. To discharge the contents of
the car the shaft 43 is released and as the
center of support of the car body is slightly
out of line with the center of gravity, it
will be automatically tilted in the direction
shown in broken lines in Fig. 4. The roll-
ing hinge members carry the car body easily
to this dumping position and the teeth 42
operating in the slots 37, prevent any slip-
ping movement. End motion of the car
body is prevented by means of the plates 38.
The doors are automatically released when
the car begins to tilt and fall downwardly
to a position which will prevent the con-

tents of the car from falling back under the
trucks. The car, when emptied, will return
by gravity to its former position. When
the car is loaded the center of support of 65
the body is nearer the closed side than the
open side thereof, so that the body tilts by
gravity to dump the load. In tilting the
body rolls on the hinge irons so that the cen-
ter of support is shifted past the center of 70
gravity toward the door side of the body.
Thus, when the load is discharged, the body
automatically rights itself, the momentum
attained in the first part of the movement
being sufficient to carry the body to a hori- 75
zontal position, where it is locked.

While I have shown the preferred em-
bodiment of my tilting and operating mech-
anism, it will be understood that several
modifications may be made without depart- 80
ing from the spirit of my invention.

Having thus described my invention, what
I claim is:—

1. A dump car of the character described
comprising a car body, an underframe hav- 85
ing a longitudinal center sill, hinge mem-
bers between the center sill and the car
body, means for tilting the car laterally
upon its hinges, discharging doors at one
side of the car, means for releasing said
doors with the tilting movement of the car,
buffers pivoted under the car body, and
means for positioning said buffers to sup-
port the discharging doors, substantially as
described. 95

2. A dump car of the character described
comprising a car body, an underframe hav-
ing a longitudinal center sill, hinge mem-
bers interposed between the car body and
the underframe, a longitudinal shaft, pin-
ions mounted thereon, a series of toothed
racks coöperating with said pinions to tilt
the car laterally, discharging doors at one
side of the car, buffers adapted to support
said doors in their lowered position and
means for positioning said buffers, substan-
tially as described. 100

3. A dump car of the character described
comprising an underframe, a car body, and
curved members supporting the car body on 110
the underframe, said members being posi-
tioned to support the car body at one side of
its center of gravity in horizontal position
and shaped to shift the center of support
to the other side of the center of gravity 115
when the body tilts.

In witness whereof I have hereunto set
my hand in the presence of two witnesses.
